CONDENSER FOR REFRIGERATING UNITS

Maxwell R. Karge, Brockport, N. Y.

Original application April 16, 1932, Serial No. 605,682. Divided and this application May 15, 1934, Serial No. 725,680

7 Claims. (Cl. 257—43)

This invention relates to the construction of refrigerating units and especially to that of the condenser thereof and has for one of its objects to provide a condenser construction which is simple in construction, efficient in operation and is built up of interchangeable parts.

Another object of this invention is to so construct the condenser that its capacity may be increased by simply increasing the length of some of the parts thereof.

A further object of this invention is to build up the condenser in such a manner that its heads provide a base for the condenser as well as the compressor units and motor drive of the refrigerating unit.

Another object of the invention is to provide the condenser with rectangularly shaped heads so that fabricated steel members can be used for connecting the heads at the top of the condenser and thus provide a base on which the compressor and its driving motor is mounted.

All these and other objects and attendant advantages will become more readily apparent from the detailed description of the invention which follows, reference being had to the accompanying drawing in which

Figure 1 is a side elevation of a refrigerating unit embodying the novel condenser construction with parts of the condenser broken away and illustrated in section.

Figure 2 is a vertical sectional view of the head at one end of the condenser and taken on the line 2x—2x of Figure 1.

Figure 3 is a vertical sectional view of the condenser taken on the line 3x—3x of Figure 1.

Figure 4 is a vertical sectional view of the other head of the condenser and taken on the line 4x—4x of Figure 1.

In the several figures of the drawing like reference numerals indicate like parts.

This application is a division of my prior application Serial No. 605,682 filed April 16, 1932 (which has matured into Patent 1,969,137) and the subject matter of the invention disclosed herein is restricted to the novel construction of the condenser of the refrigerating unit.

As illustrated in the figures of the drawing the condenser of the refrigerating unit is made up of a cylinder 1, the ends of which project into the annular grooves 2 and 3 of the rectangularly shaped heads 4 and 5 respectively. These heads are connected on the outside of the cylinder by the tie rods 6, 7, 8 and 9 and are drawn against the ends of the cylinder by means of the nuts 10, 10, a suitable packing being provided

in the annular grooves to form a tight joint between the cylinder and the heads thereof.

The cooling tubes 11 pass thru the cylinder and its heads and are anchored and sealed in the heads by means of the bushings 12 which are threaded to the ends of the cooling tubes and compress the packing surrounding the ends of the tubes in the enlarged outer portion of the holes in the heads thru which the tubes project. The ends of the tubes are thus sealed into the heads and provide individual passages thru the cylinder from one end to the other.

Held clamped to the outside of the heads 4 and 5 are the auxiliary heads 13 and 14 respectively. These auxiliary heads are drawn toward each other and against the outside of the heads 4 and 5 by means of the tie rods 15 which pass thru the center of the cooling tubes 11 and thru suitable holes in the auxiliary heads. A suitable packing is interposed between each head and its auxiliary head and the nuts 16 are threaded to the ends of the tie rods 15 on the outside of the auxiliary heads to draw the auxiliary heads against the cylinder heads proper to compress the packing between the heads and seal the joint between them.

The hollow portion of the auxiliary head 14 is divided into an upper and lower compartment by means of the central horizontal partition 17 and the hollow portion of the auxiliary head 13 is divided into an upper, lower and central compartment by means of two parallel horizontal partitions 18 and 19. In the auxiliary head 13 the partitions are arranged so that one end of the lowermost of the cooling tubes 11 is located in the lower compartment, the corresponding ends of the four intermediate tubes in the central compartment and the corresponding end of the uppermost tube in the upper compartment.

In the auxiliary head 14 the single central partition is arranged so that the opposite ends of the three lower cooling tubes 11 are located in the lower compartment thereof while the corresponding ends of the three upper cooling tubes are located in the upper compartment thereof.

The cooling water enters the auxiliary head 13 thru the inlet 20 and the water passes from the lower compartment of this head thru the lowermost cooling tube 11 into the lower compartment of the head 14. From this compartment in the head 14 the cooling water flows back to the central compartment in the head 13 thru the lower pair of the central cooling tubes and from this central compartment back to the upper compartment in the head 14 thru the upper pair of the

central cooling tubes. From the upper compartment in the head 14 the cooling water flows back into the upper compartment of the head 13 thru the uppermost cooling tube and from this compartment thru the outlet 21 thru suitable piping to the water jacket 22 of the compressor cylinder 23.

The cooling water is thus made to flow back and forth in the cooling tubes 11 within the cylinder 1 of the condenser. The passage of the cooling water thru the cooling tubes is restricted by the tie rods 15, but the cooling efficiency of the amount of condensing water which passes thru the cooling tubes is held to a maximum by spreading the reduced volume of the condensing water over the inside of the periphery of the cooling tubes to cause a quick absorption of the heat of the gases within the cylinder.

The compressor is connected with the cylinder 1 by means of the pipe line 24 which enters the condenser cylinder 1 at the top to discharge the compressed refrigerant thereinto. The refrigerant, after being condensed, leaves the condenser thru the outlet 25.

The straight bottom of the rectangularly shaped heads 2 and 3 of the condenser provide the base therefor and at the same time serve as supporting members for the compressor and its motor drive. For this latter purpose the heads support the channel member 26 at the top in such a manner that the sides thereof overhang the upper portion of the side of the heads and with the ends of this connecting member fastened to the heads this member provides an extremely rigid and strong connection between the heads to which the compressor and motor drive can be securely anchored.

I claim:

1. A condenser for a refrigerating unit comprising a tubular shell, a head having an annular groove on the inside thereof at each end of said shell to have the end of said shell engage into said groove, tie rods extending thru said heads and said tubular shell with the ends of said tubular shell nested into said annular grooves, condenser tubes passing thru said head and said tubular shell and encircling said tie rods and suitably spaced from them, bushings threaded on the outside of said condenser tubes to fasten the ends of said tubes to said heads, and auxiliary heads on the outside of said heads and connected with each other by said tie rods to clamp said auxiliary heads against said first mentioned heads and said first mentioned heads against the ends of said shell.

2. A condenser for a refrigerating unit comprising a tubular shell, a head having an annular groove on the inside thereof at each end of said shell to have the end of said shell engage into said groove, tie rods extending from one of said heads to the other thereof to clamp said heads to said tubular shell with the ends thereof nested into said annular grooves, condenser tubes pass-

ing thru said head and said tubular shell, bushings threaded on the outside of said condenser tubes to fasten the ends of said tubes to said heads, auxiliary hollow heads on the outside of said first named heads, partitions dividing the hollow space in said heads into compartments, tie rods passing thru said condenser tubes and said heads and means carried by said tie rods to draw said auxiliary heads against said first named heads with the compartments in said heads forming the connection between the ends of consecutive vertically spaced condenser tubes, said tie rods in said condenser tubes restricting the passage of condensing water between the outer surface of said tie rods and the inner surface of said condenser tubes to increase the cooling effect of the water on the condenser tubes.

3. A condenser for refrigerating units comprising a tubular shell, a head at each end of said shell, tie rods connecting said heads on the outside of said shell, cooling tubes extending thru said heads and the shell, auxiliary heads covering the ends of said cooling tubes and tie rods extending centrally thru cooling tubes to fasten auxiliary heads to the heads proper.

4. A condenser for refrigerating units comprising a tubular shell, a head at each end of said shell, tie rods clamping said heads to said shell, auxiliary heads on the outside of said heads having compartments formed therein and cooling tubes surrounding said tie rods extending from the compartments in said auxiliary heads and arranged to have the cooling water flow back and forth from one auxiliary head to the other thru said shell.

5. In a condenser for refrigerating units the combination of a tubular shell having a head at each end thereof, cooling tubes extending thru said heads and shell and a rod located centrally in said tubes and extending thru the ends thereof to cause a limited but unrestricted flow of water thru said tubes to contact a maximum area of the inside of the tubes.

6. In a condenser for refrigerating units the combination of a tubular shell, a removable head clamped to each end of said shell, a flat bottom on each of said heads to provide a base for said condenser between them, a smaller auxiliary head on the outside of each of said first mentioned heads and means for clamping said auxiliary heads against said first mentioned heads and said first mentioned heads against the ends of said shell.

7. In a condenser for refrigerating units the combination of a tubular shell, a removable head clamped to each end of said shell, a flat bottom on each of said heads to provide a base for said condenser between them, a flat connecting member connecting said heads at the top to fasten said heads together and provide a supporting base above said shell the full length of said shell.

MAXWELL R. KARGE.
